Inventor,

R. F. Metzger,
By his Attorneys,
Matthew V. Allen.

UNITED STATES PATENT OFFICE.

REINHARDT F. METZGER, OF BROOKLYN, NEW YORK.

PLIERS.

1,389,371.

Specification of Letters Patent. Patented Aug. 30, 1921.

Application filed May 10, 1921. Serial No. 468,217.

To all whom it may concern:

Be it known that I, REINHARDT F. METZGER, a citizen of the United States of America, residing at Brooklyn, Queens county, 5 New York, have invented a new and useful Pliers, of which the following is a specification.

My invention relates to an improved tool for facilitating the application of small 10 rivets to parts to be connected, the same being particularly useful in securing the shells to the guards of eye-glass nose-pieces. Such parts are very small and difficult to handle. The rivets likewise are exceedingly small 15 and correspondingly difficult to handle. By my construction, a nose guard shell may be applied in a remarkably short space of time, saving tremendously in the labor charge ordinarily involved. Furthermore, the tool 20 guarantees an effective and durable fastening. The device may be appropriately termed a riveting tool, although it performs in actual practice the function of a punch, cutter, and setting means for the rivet.

25 In the accompanying drawings,

Figure 1 is a side elevation of the tool partly in section.

Fig. 2 is a plan view of the upper jaw.

Fig. 3 is a plan view of the lower jaw.

30 Fig. 4 is a sectional view relatively enlarged, and illustrating the jaws and the associated parts as they would appear immediately following the punching operation.

Fig. 5 represents the parts as they would 35 appear when the rivet is pushed to its home position.

Fig. 6 illustrates the parts as they would appear when the superfluous end of the rivet is clipped off.

40 Fig. 7 illustrates the parts as they would appear when the rivet is being upset.

Fig. 8 illustrates the parts as they would appear when an old rivet is being pushed out.

45 1 represents the upper jaw of the riveting tool. 2 represents the lower jaw. These jaws may be provided with any means for causing the same to move to and fro, but by preference, they are associated respectively with two handles 1^a—2^a which are pivoted at 3 after the manner of a pair of pliers, so that the jaws may be moved toward and away from each other. To the lower jaw near its tip, there is a socket 4, in which a

50 rivet 5 may be seated as indicated in Fig. 4. 55 Directly opposite the socket and in the upper jaw is a hole 6. 7 is another hole preferably in the upper jaw which faces a solid part of the jaw 2. 8 is still another hole also preferably in the upper jaw which faces a 60 punch 9 carried by the lower jaw. 10—10 are cutting edges on the jaws 1—2 which function in the manner hereinafter described. 11 represents conventionally the guard of a nose-piece, while 12 conventionally represents a thin piece of shell or celluloid which is to be attached to the guard 11. The guard 11 is usually made of gold 65 or gold-plate, the rivet holes being formed therein at the time of manufacture. The 70 shell pieces are ordinarily not bored or punched at the outset, but in practice, are bored when they are applied to the guards. When using my tool for the purpose of connecting these parts, the jaws 1—2 are opened 75 up, a rivet 5 is placed in the socket 4, the guard 11 and shell 12 are placed together in the proper position, and the hole in the guard is slipped over the exposed end of the rivet 5. The jaws are then forced together 80 causing the end of the rivet 5 to act as a punch so that it will force its way through the shell 12 as shown in Fig. 4. When this is done, the jaws are again opened up, the end of the rivet is passed through the hole 85 7, and the jaws are brought together forcing the rivet into its home position shown in Fig. 5. The jaws are again opened up, the guard, shell and rivet are removed, and the surplus end of the rivet may be clipped 90 off as shown in Fig. 6. The parts are then placed in the position shown in Fig. 7 so that the jaws when brought together will upset the end of the rivet, tightly bending together the guard and shell as shown in 95 said figure. It will be understood, that the appearance of the rivets and the various parts are enlarged or exaggerated in the several views. In actual practice, these parts are so very small that the pressure of 100 the jaws 1—2 will form only a very small head on the rivet which lies practically flush with the surface of the shell so that it will not scratch or irritate the nose of the wearer.

If it is desired to replace a shell, and it 105 is necessary to force out the old rivets, this can be done in the manner shown in Fig. 8, wherein the punch 9 is shown as pushing

out an old rivet 5^a. By this very simple and handy tool, I am enabled to secure together these very small and delicate pieces in a remarkably short space of time, by which I mean, the entire work can be accomplished well inside of a minute, whereas by methods heretofore employed it has usually taken twenty minutes to perform the same work. Of course, the actual time depends somewhat upon the skill of the particular operative. By the use of my tool, a comparatively unskilled operative can successfully perform this work, whereas heretofore such work has required a skilled operator.

It will be noted that the jaws are flat faced, and it is preferable that both of the same should be comparatively thin. Hence, I provide at each side of each jaw a flanged reinforcement 14, which flanges greatly stiffen said jaws so that the same will exert the necessary pressure to be applied.

What I claim is:—

1. A riveting tool comprising, a pair of jaws with means for moving the same toward and away from each other, a socket carried by one of said jaws, the other jaw having an opening therein facing said socket, one of said jaws having an opening facing a solid part of the opposite jaw, a punch on one of said jaws, and an opening on the other facing said punch.

2. A riveting tool comprising, a pair of jaws with means for moving the same toward and away from each other, a socket carried by one of said jaws, the other jaw having an opening therein facing said socket, one of said jaws having an opening facing a solid part of the opposite jaw, a punch on one of said jaws, and an opening on the other facing said punch, and co-acting cutting edges at one side of said jaws.

REINHARDT F. METZGER.
